Letters Patent No. 2236. Dated Dec. 26. 1865.

Design for Floor oil Cloth.

The schedule referred in the Letters Patent and making part of the same.

To all whom it may concern:

Be it known that I James Paterson of City of Elizabeth, County of Union, State of New Jersey, have invented or produced a new and original Design for a pattern to be printed on Floor Oil Cloths in colors similar to those painted on the drawings accompanying this specification or in other colors substituted in the place of those painted on the drawings herewith; and I do hereby declare that the drawings accompanying this specification do give and convey to any one skilled in the art of printing Oil Cloths a more defined and thorough description of the nature of my invention than it is in the power of language to convey otherwise, and is sufficient to enable any one skilled in the art of Oil Cloth printing to use my invention.

What I claim as my invention and desire to secure by Letters Patent is the Design for Floor Oil Cloths in the form similar to the drawings accompanying this specification.
